CLAIM

The ornamental design for a ventilation grid, as shown.

DESCRIPTION

FIG. 1 is a perspective view of a ventilation grid showing a first embodiment of our new and ornamental design;
 FIG. 2 is a front view thereof;
 FIG. 3 is a rear view thereof;
 FIG. 4 is a side view thereof;
 FIG. 5 is a perspective view of a second embodiment of our design;

(Continued)

FIG. 6 is a front view of FIG. 5;
 FIG. 7 is a rear view of FIG. 5; and,
 FIG. 8 is a side view of FIG. 5.

1 Claim, 4 Drawing Sheets
